US0D1006694S

(12) **United States Design Patent** (10) **Patent No.:** **US D1,006,694 S**
(45) **Date of Patent:** **** Dec. 5, 2023**

(54) **FENDER FLARE**

(71) Applicant: **Bodyguard Products LLC**, Paris, TX (US)

(72) Inventors: **Charles Grant Mallicote**, Sumner, TX (US); **Kelli Renee Mallicote**, Sumner, TX (US); **Caleb Michael Hix**, Paris, TX (US)

(73) Assignee: **Bodyguard Products LLC**, Paris, TX (US)

(**) Term: **15 Years**

(21) Appl. No.: **29/865,666**

(22) Filed: **Aug. 5, 2022**

Related U.S. Application Data

(60) Division of application No. 29/788,696, filed on Jul. 19, 2021, now Pat. No. Des. 960,059, which is a division of application No. 29/707,736, filed on Sep. 30, 2019, now Pat. No. Des. 925,421, which is a continuation of application No. 29/665,493, filed on Oct. 3, 2018, now Pat. No. Des. 861,561.

(57) **CLAIM**

The ornamental design for a fender flare, as shown and described.

DESCRIPTION

FIG. 1 is a perspective view showing top and front surfaces of a fender flare.

FIG. 2 is a perspective view showing bottom and front surfaces thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the drawings illustrate portions of the fender flare which form no part of the claimed design.

1 Claim, 7 Drawing Sheets
